US00D689482S

(12) **United States Design Patent**
Akana et al.

(10) **Patent No.:** US D689,482 S
(45) **Date of Patent:** ** Sep. 10, 2013

(54) **PORTABLE DISPLAY DEVICE**

(75) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Iye**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **14 Years**

(21) Appl. No.: **29/432,444**

(22) Filed: **Sep. 14, 2012**

Related U.S. Application Data

(63) Continuation of application No. 29/384,911, filed on Feb. 4, 2011, now Pat. No. Des. 669,468, which is a continuation-in-part of application No. 29/382,846, filed on Jan. 7, 2011, now Pat. No. Des. 670,692.

(57) **CLAIM**

The ornamental design for a portable display device, as shown and described.

DESCRIPTION

FIG. 1 is a top front perspective view of a portable display device showing our new design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the left corner of FIG. 8;

FIG. 10 is an enlarged view of the right corner of FIG. 8;

FIG. 11 is a top front perspective view of another embodiment of a portable display device showing our new design;

FIG. 12 is a bottom rear perspective view thereof;

FIG. 13 is a front view thereof;

FIG. 14 is a rear view thereof;

FIG. 15 is a left side view thereof;

FIG. 16 is a right side view thereof;

FIG. 17 is a top view thereof;

FIG. 18 is a bottom view thereof;

FIG. 19 is an enlarged view of the left corner of FIG. 18; and,

FIG. 20 is an enlarged view of the right corner of FIG. 18.

The broken lines in the Figures show portions of the portable display device which form no part of the claimed design.

The shade lines in the Figures show contour and not surface ornamentation.

1 Claim, 14 Drawing Sheets

(57) **CLAIM**

The ornamental design for a portable display device, as shown and described.

DESCRIPTION

FIG. 1 is a top front perspective view of a portable display device showing our new design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the left corner of FIG. 8;

FIG. 10 is an enlarged view of the right corner of FIG. 8;

FIG. 11 is a top front perspective view of another embodiment of a portable display device showing our new design;

FIG. 12 is a bottom rear perspective view thereof;

FIG. 13 is a front view thereof;

FIG. 14 is a rear view thereof;

FIG. 15 is a left side view thereof;

FIG. 16 is a right side view thereof;

FIG. 17 is a top view thereof;

FIG. 18 is a bottom view thereof;

FIG. 19 is an enlarged view of the left corner of FIG. 18; and

FIG. 20 is an enlarged view of the right corner of FIG. 18.

The broken lines in the Figures show portions of the portable display device which form no part of the claimed design.

The shade lines in the Figures show contour and not surface ornamentation.
